COMBINED COLLECTION BOX AND CLOSURE LID THEREFOR

James Hendricks Brasher, Conshohocken, Pa.

Application January 27, 1953, Serial No. 23,325

Term of patent 14 years

(Cl. D34—11)

To all whom it may concern:

Be it known that I, James Hendricks Brasher, a citizen of the United States, residing at Conshohocken, in the county of Montgomery and State of Pennsylvania, have invented a new, original, and ornamental Design for a Combined Collection Box and Closure Lid Therefor, of which the following is a specification, reference being had to the accompanying drawing, forming a part hereof.

Figure 1 is a perspective view of a combined collection box and closure lid therefor, showing my new design; and

Figure 2 is a fragmentary plan view of the closure lid portion thereof.

The dominant feature of my design resides in the portions shown in full lines.

I claim:

The ornamental design for a combined collec-

tion box and closure lid therefor, as shown and described.
